DESIGN FOR A GLASS BOTTLE

Lawrence J. Kihm, Pittsburgh, Pa., assignor to
J. T. & A. Hamilton Company, a corporation of Pennsylvania

Application February 20, 1940, Serial No. 90,377

Term of patent 14 years

To all whom it may concern:

Be it known that I, Lawrence J. Kihm, a citizen of the United States, residing in Pittsburgh, in the county of Allegheny and State of Pennsylvania, have invented a new, original, and ornamental Design for a Glass Bottle, of which the following is a specification, reference being had to the accompanying drawing, forming part thereof.

Fig. I is a front elevational view of a glass bottle showing my new design.

Fig. II is a rear elevational view.

Fig. III is a side elevational view.

Fig. IV is a diagrammatic plan view showing the outline of the bottle.

I claim:

The ornamental design for a glass bottle, substantially as shown.

LAWRENCE J. KIHN.
